UNITED STATES PATENT OFFICE.

JOHN H. REIGHLEY, OF WELLSVILLE, AND WILLIAM P. SPARROW, OF MOBERLY, MISSOURI.

PORTABLE-BOX POST-OFFICE.

SPECIFICATION forming part of Letters Patent No. 760,562, dated May 24, 1904.

Application filed November 17, 1903. Serial No. 181,560. (No model.)

To all whom it may concern:

Be it known that we, JOHN H. REIGHLEY, residing at Wellsville, Montgomery county, and WILLIAM P. SPARROW, residing at Moberly, 5 Randolph county, State of Missouri, citizens of the United States, have invented certain new and useful Improvements in Portable-Box Post-Offices, of which the following is a specification.

10 Our invention relates to portable-box post-offices for rural-route mail-carriers, and has for its object to produce a device of this character which permits of alphabetical or name classifications of the mail-matter and newspaper 15 or other periodicals and which also forms a convenient receptacle for stamps, money, paper, envelops, pens, and all other supplies which it is customary or desirable for a rural-delivery postmaster to handle for the convenience 20 of himself and the public.

A further object is to produce a device of this character provided with a series of superimposed tills having their front sides and bottoms in the form of pivoted plates capable of 25 being folded against the back wall of the box, so as to enable the mail-carrier to adapt the box to receive packages of more than the usual length.

With these and other objects in view, as 30 hereinafter appear, the invention consists in certain novel and peculiar features of construction and organization, as hereinafter described and claimed, and in order that it may be fully understood reference is to be had to 35 the accompanying drawings, in which—

Figure 1 is a perspective view of a portable-box post-office embodying our invention, the box being shown open. Fig. 2 is a vertical section of the box, taken on the line II II of 40 Fig. 1, but with the box closed. Fig. 3 is a detail view of one of the pivoted plates forming the bottom and front wall of the till.

Referring to the drawings in detail, 1 designates the base, 2 the sides, 3 the back, and 4 45 the top, of the box, approximating in height and width a small trunk, but preferably narrower from front to rear, so that the box can be conveniently carried on the bottom of a buggy in front of the driver or can be lifted

up and easily placed upon the seat by his side, 50 and in either position its contents are easily accessible.

The front of the box is in the form of a door 5, hinged, by preference, at its lower end, as at 6, to the bottom and adapted to be provided 55 with a suitable padlock (not shown) to secure it in its closed position, and secured to the outer or front side of the door is a mail-pouch 7 to receive the mail collected by the carrier. The door is provided with a series of longitudinal channels 8 in its inner side, said channels being of suitable width to accommodate any ordinary letter, and bridging said channels at suitable intervals and secured by screws or tacks 9 or equivalent devices to the door are 60 canvas or other strips 10, the fabric of each strip preferably overlapping the lower edge of the strip next above, as shown. Out of the lower edge of each strip except the bottom strip are cut tongues 11, corresponding in number 65 to the channels 8 and registering therewith, said tongues extending from a point above the upper edge of the contiguous strip and having their free ends tacked or otherwise secured in the bottoms of said channels, 70 as at 12, as shown most clearly in Fig. 2. By this disposition of said tongues it will be seen that the channels 8 are divided up into a large 75 number of pockets wherein letters and postal cards may be conveniently lodged pending distribution, the number of pockets, of course, permitting of alphabetical or name classification of such mail-matter.

The body of the box is provided with a series of vertical partitions 13, the middle one 85 of which by preference terminates at its lower end on cross-piece 14, which cross-piece will form the top of a drawer 15, provided with cleats 16 to engage grooves 17 in the proximate faces of the contiguous partitions 13, as 90 shown most clearly in Fig. 1, this drawer being adapted to contain stamps, money, stamped and unstamped envelops, pens, and other supplies. Between the partitions 13 the back wall of the box is preferably provided in its 95 front or inner side with recesses 18, which in width extend from partition to partition or from partition to side wall and in height

equal that of the plates 19, hinged, as at 20, in the lower ends of said grooves, said plates 19 being provided near their upper ends with outwardly - projecting lugs 21, engaging 5 grooves 22, formed in the contiguous slots concentric of hinge-points 20. The parts just described constitute a series of superimposed tills, of which plates 19 form the bottom and front sides, the lugs 21 by contact with the 10 front ends of the grooves serving to hold said plates at the desired angle with reference to the back. When it is desired to provide a till of depth to accommodate a package too long to be properly held in any one of the 15 tills, the bottom of one of the top series of tills can be swung rearwardly into the registering recess 18 of the back wall, as indicated in dotted lines, Fig. 2. By so doing it will be obvious that space is provided which will 20 accommodate a very long package. In case the latter is about as long as the interior height of the box the bottoms of a full set of superimposed tills can be swung to inoperative position, so that said package can rest 25 upon the bottom of the box, as will be readily understood. For convenience in handling the box it is provided with a handle 23 at its upper end.

A portable-box post-office of the type described possesses all of the advantages of the 30 wagons built expressly for rural - delivery mail - carriers and is far preferable to such wagons, because the latter are expensive and cannot be used to advantage for any other 35 purpose than the delivery of mail. The carrier equipped with this box can place it in his buggy and after delivery or collection hours can deposit it with the supervising postmaster and have the buggy for any other use he 40 may desire. Ordinarily the box would be placed in the bottom of the buggy contiguous to the dashboard; but in case of rain or for any other reason it could be conveniently deposited upon the seat beside the driver, where 45 it would be more fully protected.

From the above description it will be apparent that we have produced a portable-box post-office for rural-delivery mail-carriers embodying the features of advantage enumer-

ated as desirable in the statement of invention and which is also of simple, strong, durable, and inexpensive construction.

It is to be understood that various changes may be resorted to in its form, proportion, detail construction, and arrangement of the parts 55 without departing from the principle of construction involved.

Having thus described the invention, what we claim as new, and desire to secure by Letters Patent, is—

1. A box post-office, comprising a box, having a hinged door provided at its inner side with a series of longitudinal channels, and with a series of flexible strips bridging said channels; each strip having its upper end overlapping the lower end of the next strip above, and each strip above the bottom one having tongues cut out of its lower end which are secured to the bottoms of the registering channels.

2. A box post-office, comprising a box having a door, and provided with vertical partitions, and with segmental grooves in the opposing faces of the partitions and the side walls, plates having their lower ends contiguous to the back wall and hinged at said ends concentrically of said grooves and provided with laterally-projecting lugs engaging opposite grooves.

3. A box post-office, comprising a box having a door, and provided with vertical partitions, and with segmental grooves in the opposing faces of the partitions and the side walls, and with recesses in the back wall with which the rear ends of said grooves register, 80 and plates having their lower ends contiguous to the back wall and hinged at said ends concentrically of said grooves and provided with laterally-projecting lugs engaging opposite grooves; said plates being adapted to swing 85 back into said recesses.

In testimony whereof we affix our signatures in the presence of two witnesses.

JOHN H. REIGHLEY.

WILLIAM P. SPARROW.
